UNITED STATES PATENT OFFICE

122,701

DESIGN FOR A FINGER RING

Herbert R. Terryberry and Arthur P. Terryberry, Grand Rapids, Mich.

Application July 17, 1940, Serial No. 93,727

Term of patent 7 years

To all whom it may concern:

Be it known that we, Herbert R. Terryberry and Arthur P. Terryberry, citizens of the United States, residing at Grand Rapids, in the county of Kent and State of Michigan, have invented a new, original, and ornamental Design for a Finger Ring, of which the following is a specification, reference being had to the accompanying drawing, forming a part thereof.

Figure 1 is a front elevational view of a finger ring showing our new design;

Figure 2 is a left-hand side elevational view thereof;

Figure 3 is a right-hand side elevational view thereof; and

Figure 4 is a top plan view thereof.

The essential features of my design reside in the ring shank shown in full lines. The initials shown on the drawing are merely illustrative, it being understood that other letters may be substituted therefor.

We claim:

The ornamental design for a finger ring, substantially as shown and described.

HERBERT R. TERRYBERRY.
ARTHUR P. TERRYBERRY.
